UNITED STATES PATENT OFFICE.

HARMON SCHLEY RICHARDSON, OF MASSILLON, OHIO.

AUTOMOBILE-DOOR LATCH.

1,347,229.

Specification of Letters Patent. Patented July 20, 1920.

Application filed November 5, 1919. Serial No. 335,853.

To all whom it may concern:

Be it known that I, HARMON S. RICHARDSON, a citizen of the United States, residing at Massillon, in the county of Stark and State of Ohio, have invented certain new and useful Improvements in Automobile-Door Latches, of which the following is a specification.

This invention relates to fasteners for hinge closures, and the primary object of the invention is to provide an improved automobile door lock or latch which will be simple and easy to operate and which will present a pleasing appearance to the eye.

Another object of the invention is to provide an improved automobile door lock, which is so constructed, that the occupant of the vehicle can tell by glancing at the lock whether or not the same is in locked position and thereby eliminate the annoyance and the damage caused by the doors swinging open when the vehicle is in motion.

A further object of the invention is the provision of an improved door latch which is practically noiseless in operation, one which is durable and efficient in use, and one which can be manufactured and placed upon the market at a reasonable cost.

Other objects of the invention will appear in the following detailed description, taken in connection with the accompanying drawings, forming a part of this specification and in which drawings:

Figure 1 is a fragmentary perspective view of an automobile body showing the approved lock applied thereto in unlocked position.

Fig. 2 is a large detail perspective view of the lever or latching bar, and

Fig. 3 is a fragmentary end elevation partly in section of a vehicle door showing the latching bar in locked position.

Referring to the drawings, in detail wherein similar reference characters designate corresponding parts throughout the several views, the letter A indicates a motor vehicle body having the usual hinged closure B provided with the improved lock C. The lock C includes substantially the locking lever or latch D, the keeper E, and the receiving guide saddle or casing F for the latch bar. For the purpose of illustration, the latch bar D is shown carried by the hinge closure B and the keeper E by the panel of the automobile body A, but it is to be understood that the parts may be reversed and the keeper E carried by the door closure B and the latch bar D carried by the upper end of the panel.

The hinged closure B is of the ordinary or any preferred construction and it has its upper edge provided with the usual rail or gunwale 5, the forward end of which is cut away as at 6 for the reception of the lever or latch bar D. The upper edge of the door B where the rail 5 has been cut away is provided with a longitudinally extending groove 7 which opens out at the free edge of the door and the groove extends adjacent to the inner longitudinal edge of the door. The groove 7 is provided for the reception of the guard channel or housing F, which will be hereinafter more fully described.

The latching bar D includes the substantially rectangular plate 8 having the depending side flanges 9 formed on the longitudinal edges thereof and adapted to engage the upper edge 6 of the closure and serve as a continuation of the rail or gunwale 5. A longitudinally extending depending rib or bar 10 is formed on the lower surface of the plate 8 and extends adjacent to the inner longitudinal edge thereof and is adapted to snugly fit in the housing or guide channel F. The rear end of the rib 10 is extended beyond the plate 8 and rounded to form the ear 11 which is provided with the aperture 12 for the reception of the pivot pin 13, which extends transversely through the door closure. This permits the forward end of the latching bar or lever to be readily raised. As clearly shown in Figs. 1 and 2 of the drawings, the side flanges 9 are rounded so as to present a pleasing appearance, and permit the same to be readily grasped by the hands of the operator to permit a firm grip to be had on the same. The keeper E includes the flat body provided with suitable transverse apertures for the reception of fastening elements 15 whereby the same may be readily secured in place. The panel of the automobile body is preferably notched as 16 adjacent its upper edge, so that the

outer surface of the keeper will extend flush with the outer edge thereof. The lower face of the body rests on the lower wall of the notch 16 of the panel with its inner face in abutting relation to the vertical wall thereof, and the upper edge of the same extends below the upper edge of the panel.

The upper surface of the keeper E is provided with the nose 17, the rear end of which is provided with the abrupt shoulder 18, which forms an abutment for the forward edge of the rib or bar 10 to rest against, so as to prevent outward movement of the door when the bar is in its latched position. The forward end of the nose 17 is provided with the downwardly inclined face 19, which forms means for raising the latching lever D, when the door is thrown closed.

20 To facilitate the closing movement of the door by the lifting of the latch bar D, the forward end of the same is provided with an anti-friction roller 20 which is adapted to engage the inclined face 19 during the opening and closing movement of the door. The forward end of the rib is provided with a recess 21 for reception of the roller which is mounted on the pin 22 which extends transversely of the recess 21. The 25 lower edge of the roller sets slightly below the lower face of the rib as clearly shown in Figs. 2 and 3 of the drawings. To further facilitate the easy and noiseless operation of the lever, the inner wall of the longitudinal groove 7 is recessed for the reception of an anti-friction roller 23, which is mounted upon a pivot pin 24 carried by the guide channel or housing.

The guide channel or casing F includes a 30 channel shaped body 25 which as hereinbefore stated is snugly fitted in the groove 7 and held in position by any suitable or preferred means. The channel shaped body 25 forms a guide for the bar 10 and prevents wear on the inner surface of the groove. One wall of the channel shaped body 25 adjacent the forward end thereof is provided with the struck out ears 26 which are arranged in spaced parallel relation to each other. These ears 26 are arranged in the recess formed in the side wall of the groove and they form supports for the pivot pin 24. The ears 26 engage the side walls of the recess and provide means 35 for preventing longitudinal movement of the body 25 in the groove.

While the lock has been essentially designed for closures for motor vehicles, it is to be understood that the same can be effectively used in connection with any other type of closure, such as a gate or the like.

In operation of the device, it is merely necessary to press the door B in closed position when it is desired to lock the same, 40 and it will be seen that the latching lever

D will be readily raised owing to the anti-friction roller 20 engaging the inclined surface 19 of the keeper.

When it is desired to open the door B it is merely necessary to grasp the forward 45 end of the lever D and to raise the same above the shoulder 18 of the keeper.

In practice, I have found that the form of my invention illustrated in the accompanying drawings, and described in the above description, as the preferred embodiment, is the most efficient and practical, yet realizing the conditions concurrent with the adoption of my device will necessarily vary, I desire to emphasize the fact that various minor 50 changes, in details of construction, proportion and arrangement of parts, may be resorted to when required, without sacrificing any of the advantages of my invention as set forth.

85 What is claimed as new is:

1. A latch for automobile doors including a keeper, a casing, a latching lever carried by the casing, a longitudinal rib formed on the lever and arranged to engage the casing 90 to prevent the lateral movement of the latching lever in relation to the casing, the forward end of the rib being adapted to engage the keeper.

2. A latch for automobile doors comprising a keeper, a latching lever including a plate, a depending rib extending longitudinally of the plate, a pivot ear formed on the rear end of the rib, and an anti-friction roller carried by the forward end of the rib 100 arranged to engage the keeper.

3. An automobile door latch comprising a keeper, a latching lever including a flat plate, a depending rib extending longitudinally of the plate and formed integral therewith, an anti-friction roller carried by the forward end of the rib and arranged transversely of the same for engagement with the keeper.

105 4. A latch for automobile doors comprising a keeper, a locking lever including a horizontally arranged plate arranged substantially flush with the upper surface of an automobile body when in a latched position, a depending rib formed longitudinally of the plate, the forward end of the rib being adapted to engage the keeper, and depending flanges formed on the longitudinal edges of the plate arranged to engage the side edges of the vehicle body when the lever is 115 in position.

5. An automobile latch comprising a keeper, a latching bar including a flat plate arranged to extend flush with the upper surface of the vehicle body, a longitudinally 125 extending rib formed in the lower surface of the plate, a pivot ear formed on and extending rearwardly of the rib, means pivotally securing the ear in place to hold the lever in position, and means formed on the 130

plate arranged to engage the upper edges of the vehicle body to prevent lateral movement of the plate in relation to the vehicle body when the lever is swung on said pivot 5 means when the lever is in locked position.

6. The combination with a motor vehicle body including a hinged closure, of a latch for the hinged closure including a keeper, a latch bar arranged to engage the keeper 10 having its upper surface arranged flat with the upper edge of the body.

7. The combination with a motor vehicle body, including a hinged closure, of a fastener therefor including a keeper fitted in 15 a recessed portion of the body and arranged below the upper edge thereof, a pivoted lever arranged to extend flush with the upper edge of the body and to form a continuation of the rail thereof, a depending rib 20 formed in the lower edge of the lever arranged to extend longitudinally of the same, the body having a longitudinally extending

groove arranged to receive said rib, the forward end of the rib being arranged to engage the keeper to hold the door in closed 25 position, an anti-friction roller carried by the forward end of the rib to facilitate the latching movement of the lever, and an anti-friction roller rotatably mounted in the side wall of the groove to facilitate the positioning of the rib in said groove as and for the purpose specified.

8. An automobile door latch comprising a keeper, a latching lever arranged to extend flush with the upper surface of the rail of a 35 vehicle body, the forward end of the lever being adapted to engage the keeper, and flanges formed on the lever and arranged to engage the side edges of the body to prevent relative lateral movement of the lever in relation to the body when the lever is in its 40 locked position.

HARMON SCHLEY RICHARDSON.
